Application December 2, 1936, Serial No. 66,247

Term of patent 3½ years

To all whom it may concern:

Be it known that I, Mary Mullen, a citizen of the United States, residing at Philadelphia, in the county of Philadelphia and State of Pennsylvania, have invented a new, original, and ornamental Design for a Dress, of which the following is a specification, reference being had to the accompanying drawing, forming part thereof.

Figure 1 represents a front elevational view of the dress embodying the design.

Figure 2 represents a rear elevational view of the dress embodying the design.

Figure 3 represents a fragmentary perspective view on an enlarged scale of the front shoulder portion of the dress embodying the design.

The characteristic feature of the design is the arrangement of the three elongated triangular segments in the skirt section, terminating at the waist-line, and the arrangement of the ornamentation at the hem portion thereof.

I claim:

The ornamental design for a dress, as shown and described.

MARY MULLEN.
